Attorney

UNITED STATES PATENT OFFICE.

ALVIN C. ELLIOTT, OF GRAND FORKS, NORTH DAKOTA.

LEVEL.

Application filed January 30, 1922. Serial No. 532,703.

To all whom it may concern:

Be it known that I, ALVIN C. ELLIOTT, a citizen of the United States, residing at Grand Forks, in the county of Grand Forks 5 and State of North Dakota, have invented certain new and useful Improvements in Levels, of which the following is a specification.

This invention relates to levels of the 10 gravity type, in which a swinging gravity actuated bob or pointer is utilized in lieu of the ordinary spirit level tube, and the primary objects of the present invention are, first, to provide a novel gravity level which 15 can be used effectively as a miter square, and which will give the angle of inclination of a surface on which the level is placed; second, to provide a novel means for mounting the bob or pointer in the stock; and 20 third, to provide a novel means for incorporating the protractors which cooperate with the bob or pointer and the protecting glasses in the stock, said means allowing the quick and easy association of the various parts in 25 the stock.

A further object of the invention is to provide an improved gravity level of the above character, which will be durable and efficient in use, one that will be simple and 30 easy to manufacture, and one which can be placed upon the market at a reasonable cost.

With these and other objects in view, the invention consists in the novel construction, 35 arrangement and formation of parts, as will be hereinafter more specifically described, claimed and illustrated in the accompanying drawings, forming a part of this specification, in which drawings:

40 Figure 1 is an elevation of the improved level.

Figure 2 is a central transverse section through the same, taken on the line 2—2 of Figure 1.

45 Figure 3 is a fragmentary longitudinal section through the improved level taken on the line 3—3 of Figure 2.

Figure 4 is an enlarged fragmentary transverse sectional view through the 50 improved level, illustrating the means of incorporating the bob or pointer with the stock, to permit the free swinging movement thereof, and

55 Figure 5 is a detail transverse section taken on the line 5—5 of Figure 4.

Referring to the drawings in detail,

wherein similar reference characters designate corresponding parts throughout the several views, the letter A indicates the improved level, which includes the stock B, the 60 pointer or bob C, the protractor plates D and E, the protecting glasses F, and the retaining rings G.

The stock B can be of any desired length and formed of any desired material, preferably of hard wood, such as mahogany or maple and the terminals of the stock can be provided, if so desired, with end caps 10. The longitudinal edges 11 of the stock, are of course provided with smooth plane outer 70 surfaces, which are arranged in parallel relation to each other. The stock B, at a point intermediate its ends, is provided with a transverse opening 12 and the wall of the opening at the opposite ends thereof is rabbed as at 13, to provide the stop shoulders 75 14.

The pointer or bob C includes a hinge barrel 15, a depending shank 16, and a weighted indicating arrow shaped head 17. The barrel 15 has one end thereof closed by an end wall 18, which is provided with a concentric opening for the reception of the supporting shaft 19. The opposite end of the barrel 15 is provided with a closing cap 20, which is 80 provided with a concentric opening for receiving the shaft 19. The cap 20 can be held in position by suitable retaining elements, such as machine screw 21. In order to permit the free swinging movement of the 85 pointer or bob C, suitable anti-friction elements, such as roller bearings 22, are interposed between the shaft 19 and the barrel 15, as clearly shown in Figures 4 and 5 of the drawings. The shaft 19 can be formed 90 of hard tool steel, but it is preferred that the pointer or bob C be formed of brass or some other metal, which will not be attracted by magnetic influences. The terminals of the shaft 19 extend beyond the barrel 15 and it 95

is preferred that these shaft terminals be seated in friction plugs 23, such as rubber, which may be embedded in the protecting glass plates F, which will be hereinafter more fully described.

The plates F are preferably formed of plate glass, but any other suitable transparent material may be utilized, such as celluloid, or the like, and these plates are of a disc formation and have the inner faces 105 thereof provided at their axial centers with recesses 24 for the reception of the

plugs 23. It can be seen that the plugs 23 will tend to hold the shaft 19 against rotation. Thrust bearings 25 can be provided for the terminals of the barrel 15, and these 5 thrust bearings consist of ball bearing races 26, which are mounted upon the shaft 19, and these races support ball bearings 27, which are adapted to engage the outer surface of the cap 20 and the outer surface of 10 the end wall 18 of the barrel. If so desired, washers 28 may be placed on the shaft terminals intermediate the ball bearing races 26, and the protecting glass plates F, and the inner faces of these washers may be 15 ground smooth or polished, while the outer faces may be left rough for frictionally engaging the plugs 23.

The protractors D and E, are of course, constructed identically the same, and include 20 annular plates 30, the outer faces of which may be graduated to define the degrees of a circle, and these annular plates may be formed of metal or any other suitable material possessing the necessary qualifications. These protractors D and E are 25 adapted to fit against the shoulders 14 in the rabbeted portions 13 of the stock C, and after the same has been placed in position, the protecting plates F are then placed in 30 the rabbeted portions 13 against the same. It is preferred that annular resilient friction rings or seats 31 be provided for the edges of the transparent plates F, and these seats are preferably formed of soft rubber, 35 having the inner faces thereof grooved as at 32, in which the plates F are adapted to fit. It can be seen that these seats 31 not only tend to hold the transverse plates in position, but also form a soft seat for the same 40 so as to prevent breakage thereof.

The means G provided for holding the various parts of the level in position consists of annular plates 33 and 34, which fit 45 against the opposite faces of the stock B, and extend inwardly of the walls of the opening 12 and engage the resilient seats 31 of the transparent plates F and hold these plates and the other portions of the level against displacement. The plates 33 and 34 can be 50 made of metal and are held in position against accidental displacement by suitable retaining elements, such as wood screws, 35.

It is apparent from the foregoing, that an exceptionally simple means has been provided 55 for holding the various parts of the level in position, said means allowing the quick and easy assembling of the said parts.

In assembling of the level, one of the protractors, say the protractor D is first placed 60 in position against one of the shoulders 14, after which the protecting plate is placed against the same, and the retaining ring 33 screwed into position. The barrel 15 is then placed on the shaft 19 and one of the ball bearing races 25 is placed on the shaft termi-

nal, and a washer 28 placed against the same. A friction plug 23 is then placed in the opening 24 in the glass plate which has been placed in position and the mentioned shaft terminal 19 is inserted in the plug. 70 After this shaft 19 has been placed in position, the other ball race 25 may be placed on the other shaft terminal with the washer 28 against the same. The other glass plate is then inserted in the rabbeted portion at an 75 incline until the other shaft terminal rides into the socket provided in the resilient plug 23 after which the plate may be clamped in position by the ring 24.

It also can be seen that the manner of 80 mounting the bob or pointer D allows the free swinging movement thereof under all conditions and thus a true reading of the bob or pointer may be at all times obtained.

Changes in details may be made without 85 departing from the spirit or scope of this invention; but,

I claim:

1. A gravity level comprising a stock having a transverse opening therein, the wall 90 of the opening having its opposite ends rabbeted thus providing stop shoulders, annular protractor plates fitted in the rabbeted portions against said shoulders, transparent guard plates fitted in the rabbeted portions 95 against said protractor plates, the inner faces of the transparent guard plates having axially disposed recesses formed in the inner faces thereof, friction socket plugs fitted in said recesses, an axially disposed shaft having its terminals disposed in the friction sockets, removable means for holding the transparent plates in position in said rabbeted portions against said protractor plates, a gravity operated bob including a 100 barrel for receiving said shaft, an indicating head, and a connecting shank, bearings disposed between the barrel and the shaft, and thrust bearings disposed on said shaft intermediate the barrel and the transparent 110 plates and the friction plugs carried thereby, the friction plugs forming means for holding the shaft against rotation.

2. A gravity level comprising a stock having a centrally disposed transverse opening 115 therein, the wall of the opening having its opposite ends provided with rabbeted portions defining stop shoulders, annular protractor plates disposed in the rabbeted portions against said shoulders, transparent 120 guard plates, annular friction seats surrounding the edges of said transparent plates, the plates being fitted in the rabbeted portions against said protractor plates, removable retaining rings secured to the 125 stock and engaging the annular friction seats, the transparent plates having the inner faces thereof provided with axially disposed recesses, friction sockets fitted in said recesses, a transversely disposed shaft hav- 130

ing its terminals fitted in said sockets, a gravity operated pointer including a barrel, an indicating head, and a connecting shank, the barrel being fitted upon the shaft, roller

5 bearings disposed in said barrel around said shaft, washers disposed on said shaft and engaging said friction sockets, and thrust bearings disposed about said shaft and engaging said washers and the terminals of 10 said barrel, the friction sockets forming means for holding the shaft against rotation.

3. A lever comprising a stock having a transverse opening therein, annular graduated plates disposed in said opening at the 15 opposite ends thereof, transparent guard plates fitted in the opposite ends of the opening against said graduated plates, means for removably holding the transparent guard 20 plates in position, a transversely extending axially disposed shaft arranged in said opening and supported by said transparent plates, a gravity operated bob including a barrel for receiving the shaft, an indicating 25 head, and a connecting shank, bearings dis-

posed between the shaft and the barrel, and thrust bearings disposed on the shaft intermediate the transparent guard plates and the terminals of the barrel.

4. A gravity level comprising a stock having a centrally disposed transverse opening therein, the wall of the opening having its opposite ends provided with rabbeted portions defining stop shoulders, annular protractor plates disposed in the rabbeted portions against said shoulders, transparent guard plates, annular friction seats surrounding the edges of said transparent plates, the plates being fitted in the rabbeted portions against said protractor plates, removable 30 retaining rings secured to the stock and engaging the annular friction seats, the transparent plates having the inner faces thereof provided with axially disposed recesses, friction sockets fitted in said recesses, a transversely disposed shaft having its terminals 35 fitted in said sockets, and a gravity operated bob carried by said shaft.

ALVIN C. ELLIOTT.
